(57) **CLAIM**

The ornamental design for a safety grip, as shown and described.

DESCRIPTION

FIG. 1 is a perspective view of a safety grip on a handle showing my new design.

FIG. 2 is a top view thereof;

FIG. 3 is a front elevation view thereof;

FIG. 4 is a side elevation view thereof; and,

FIG. 5 is a back elevation view thereof.

The broken line showing of a clamp is for illustrative purposes only and forms no part of the claimed design.
